(57) **CLAIM**

The ornamental design for a ring with rotatable and interchangeable elements, as shown and described.

DESCRIPTION

FIG. 1 is a top, front and left side perspective view of a ring with rotatable and interchangeable elements showing my new design;

FIG. 2 is an exploded perspective view thereof;

FIG. 3 is a front elevational view thereof with the rotating elements shown in an alternate position;

FIG. 4 is a side elevational view thereof;

FIG. 5 is a side elevational view thereof with the rotating elements shown in an alternate position rotationally offset;

FIG. 6 is a top plan view thereof;

FIG. 7 is a bottom plan view thereof;

FIG. 8 is a front elevational view thereof; and,

FIG. 9 is a rear elevational view thereof.

The broken lines in FIG. 2 showing the manner in which the ring is assembled are for reference and form no part of the claimed design. The remaining broken lines shown in the drawings illustrate portions of the ring with rotatable and interchangeable elements that form no part of the claimed design.
